UNITED STATES PATENT OFFICE.

HALCYON SKINNER AND EUGENE TYMESON, OF YONKERS, NEW YORK,
ASSIGNORS TO THE ALEXANDER SMITH & SONS CARPET COMPANY,
OF SAME PLACE.

LOOM FOR WEAVING CHENILLE, &c.

SPECIFICATION forming part of Letters Patent No. 400,260, dated March 26, 1889.

Application filed February 7, 1887. Serial No. 226,837. (No model.)

To all whom it may concern:

Be it known that we, HALCYON SKINNER and EUGENE TYMESON, both of Yonkers, in the county of Westchester and State of New York, have jointly made an invention of certain new and useful Improvements in Looms for Weaving Chenille and for other Purposes; and we do hereby declare that the following, in connection with the accompanying drawings, is a full, clear, and exact description and specification of the same.

The object of the invention is more particularly to enable the chenille or fur which is used in the manufacture of chenille carpets to be woven with facility and rapidity by power; but the invention is applicable to the weaving of other articles or goods.

It has been customary to weave chenille in a series of laterally-connected strips or strands constituting a broad web of fabric, which is subsequently cut longitudinally into separate strips, each of which constitutes a strand of chenille or fur which is used as filling in the weaving of a chenille fabric, and this practice is followed with the mechanism which we are about to describe.

In order that a pattern may be produced in the chenille carpet or other fabric, the color or shade of the chenille is varied in the operation of weaving it by the employment of yarns of the required different colors or shades. These yarns constitute the filling of the web in the weaving of the chenille, and they are tied together by warp-threads; and when the strands are cut apart and woven into the carpet or other chenille fabric the colored yarns of the fur form the pile of the fabric. When the web is cut longitudinally, each strip or strand of chenille consists of a set of warp-threads with the filling of colored yarns, and in the operation of weaving the web of chenille the adjacent sets of warp-threads are separated by spaces, so that the portions of the filling-yarns extending between the adjacent sets are as long when cut in two cross-wise as is required to form the pile of the chenille strands.

The general mode of operation of our invention is that the different varieties of col-

ored yarns required for the weaving of the chenille are wound in cops or in balls, and are held in a shifting yarn-holder having as many yarn cases or divisions as there are varieties of yarns required for the chenille, and as each shade or color of yarn is required in weaving the yarn-case containing it is placed opposite the position for weaving by shifting the yarn-holder, after which the yarn from that case is drawn across the loom and is interwoven with the warp-threads. By operating in this manner a large number of colors or shades of yarn can be held in a comparatively small space, and the employment of a large number of shuttles (one for each shade or color of yarn) is dispensed with. After a yarn is drawn across the loom the portion of it required for the web is cut loose from the residue in the yarn-holder, so that the latter is left free to be turned to place the next required cop of yarn in the position for weaving; and in order that the selvage at the opposite side of the web may be even, whatever surplus yarn may project beyond the proper line is cut off.

Our invention consists of certain mechanical devices and combinations by which the above mode of operation is worked out, and which are set forth in the claims at the close of this specification. In order that these may be fully understood, we have represented in the accompanying drawings, and will proceed to describe, the best form of loom which we have thus far devised to embody our invention, it being understood that the mechanism may be varied as circumstances or the views of different constructors or users render expedient, and that our combinations are not restricted to the peculiarities of the combining devices or power-transmitting mechanism by means of which the members are combined and caused to operate in the required order.

Figure 1 of the said drawings represents a front view of the said loom. Fig. 2 represents the right-hand side of the loom. Fig. 3 represents the left-hand side of the loom. Fig. 4 represents a fractional plan of the loom. Fig. 5 is a section of parts of the loom, showing more particularly the inner end of the

yarn-holder and the yarn-cutting mechanism. Fig. 6 is a detached view of the yarn-tension. Figs. 7 and 8 are transverse sections of parts of the loom, showing different positions of the heddles and their appurtenances. Fig. 9 is a view of parts of the wire doup-heddles, enlarged as compared with Figs. 7 and 8. Fig. 10 is a transverse section of parts of the loom, showing more particularly the lay mechanism and selavage-shears. Fig. 11 is a front view of the nippers-opener, and Fig. 12 is an end view thereof. Fig. 13 is a section of one of the yarn-cases of the yarn-holder with its yarn-tube. Figs. 14, 15, and 16 are views of the yarn-drawer for drawing the yarn across the loom. Figs. 17, 18, 19, and 20 are views showing the nippers in different positions, as hereinafter more particularly described.

In consequence of the small scale upon which drawings for patents have to be made each set of warp-threads for a strand of chenille is represented by a single line in Figs. 4, 17, 18, 19, and 20 of the said drawings. The dents of the reed and the heddles, also, are represented as less numerous than they are in the working-loom.

The various moving parts of the loom are connected and combined by the main frame A, and we prefer to effect the movements of the moving devices in some cases by means of cams alone and in others by means of cams and springs operating antagonistically, the motion being transmitted to the working members by means of levers and rods or straps. The cams are secured to the cam-shaft B, which is mounted in bearings upon the main frame, and is connected by a cog-wheel, b, and pinion b' with the driving-shaft B', to which the power is applied in the customary manner by a belt and pulleys. Each strip of chenille in the present case has a set of six warp-threads; and in order that raveling may be prevented after the web is cut up into strands two warp-threads of each set (one at each side of the set) are shifted or twined alternately inside and outside or right and left of the respective next adjacent two warp-threads of the set, as is practiced in what is called "gauze-weaving," these twined warp-threads being operated for this purpose by means of doup-heddles. In consequence of this mode of operation a longer length of the twined warp-threads of each set is used up in weaving than of the other warp-threads; hence the warp-threads are wound upon two warp-beams—the one C for the twined or doup warp-threads of each set and the other warp-beam, C', for the remaining four warp-threads of each set. These warp-beams are fitted, in practice, with the usual face or brake to prevent the warp from coming off too freely, which fittings, being well known, are not represented, to avoid complexity. The warp-threads from the warp-beams are conducted over whip-rolls D D', through the frames of heddles E E' E'', and through the reed F of the lay F', over the breast-beam G to the cloth-roll H,

which is provided in practice with the usual take-up, which, being well-known, is not represented in the drawings.

The mode of operating the heddles will be described hereinafter. The colored yarns which form the filling of the fabric are wound in cops or balls, cops being preferred, and are held at one side of the loom (in this case the left-hand side thereof) in the shifting yarn-holder I. Each yarn as required for weaving is drawn across the loom by means of a reciprocating yarn-drawing device, J, which seizes the end of the yarn projecting from the yarn-holder, draws the yarn across the loom, and then releases it. We prefer to construct the shifting yarn-holder I in a cylindrical form, as represented in the drawings, so that it may be shifted by turning it upon its axis.

The yarn-holder comprises a series of divisions or yarn-cases, i, each large enough to hold a cop of yarn, (or a ball if the yarn be wound in balls,) and in order that the amount of shifting may be as small as possible we prefer to arrange the yarn-cases in two parallel rows, i i. In order that the end of yarn from each yarn-case may be presented to the yarn-drawing device or needle, we fit each yarn-case with a yarn-tube, i', through which the yarn is conducted and from the beak or nozzle i² of which it protrudes. In order that the yarn may not render too freely when drawn from the yarn-case, each yarn has tension put upon it between the yarn-case and the end or nozzle of the tube. For this purpose the nozzle of each yarn-tube is separated from the residue by a narrow space, in which is inserted a yarn-tension device, which we prefer to make of a piece of thick felt, K, through which the yarn is passed. The friction of the felt upon the yarn makes tension upon it when it is drawn through the felt, and this tension may be enhanced by means of a tension-spring, k, which is arranged in the proper position to bear upon the felt and press it when the yarn-tube is at the weaving position, or in the proper position to have the yarn drawn from it by the reciprocating yarn-drawing device or needle.

The yarn-holder I may be shifted by the hand of an operator or by power. For simplicity we prefer to have the yarn-holder shifted by an operator, and in order that he or she may do this with facility each yarn-case is numbered, and a movable index, L, of these numbers is applied to the yarn-holder, a pointer, l, being secured to the frame of the loom, so that when any number of the index is opposite the pointer l the nozzle of the yarn-tube of the corresponding number of the yarn-cases is in the weaving position.

To facilitate the work of shifting the shifting yarn-holder, we find it expedient to use an additional index, which faces the operator. This face index M consists of a segment, the face of which is graduated and numbered, as seen in Figs. 1 and 4, with numbers corresponding with those of the yarn-cases of the

shifting yarn-holder. A movable pointer, m , is provided for this additional face index, and this pointer is secured to a rock-shaft and is connected with the shifting yarn-holder 5 through the intervention of a pinion, m' , secured to the shaft of the yarn-holder, and the segment m^2 , which is geared into said pinion and is connected by an arm with the rock-shaft of the pointer. When the shifting yarn-holder is moved backward or forward from the zero-point between the yarn-cases of the lowest and highest numbers, the pointer m is moved correspondingly along the graduations of the face index M . It is obvious that the 10 same practical result will be attained by securing the graduated segmental face index M to the arm of the pointer m , and making fast the pointer m itself to the frame of the loom.

20 The yarn-holder can be readily shifted by applying the hand to it. In order that it may be stopped and may be held in position during the seizing and drawing out of the yarn from the desired yarn-case, a stop, N , is provided. We prefer that this stop should be of the pawl variety, and in the example represented in the drawings its beak is fitted to engage in the spaces between the nozzles i^2 of the yarn-tubes, which act as teeth for the 25 stop or pawl. The stop N is pivoted to the frame of the loom, and in order that it may be readily operated it is connected by a rod, n , with a treadle, N' , to which the operator can apply his foot for the purpose of disengaging the stop, to permit the yarn-holder to 30 be shifted, while the relaxation of pressure upon the treadle permits the pawl to be engaged with the nozzles by the action of a spring, n' , and to stop the revolution of the 35 yarn-holder.

40 When the shifting yarn-holder is charged with yarns, the end of each cop of yarn is passed through the yarn-tube, as represented in Fig. 13, and is left protruding from the nozzle of the yarn-tube, so that it may be readily seized by the yarn-drawing device and drawn by it through the shed of warp-threads, which is opened for the purpose by the movement of the heddles. The yarn-drawing device or needle J , which we have used with success for the purpose, consists of a pair of spring-nippers, j , mounted at one end of a reciprocating rod or stem, j' , by which the nippers are pushed through the shed from the 45 side of the loom opposite that at which the shifting yarn-holder is located, and are drawn back again with the yarn. The nippers j (more particularly represented at Figs. 14, 15, and 16) have spring-jaws secured to a shank, j^2 , 50 which is fitted to slide in the end of the tubular rod or stem j' and is pressed endwise by a spiral spring, j^3 , the distance to which the nippers can be moved by the spring being limited by a cross-pin, j^4 , Figs. 14 and 16, that 55 passes through a slot in the npper-shank. This yarn-drawing device or needle is operated at the proper times by means of the draw-

cam J' , Figs. 1 and 2, which is secured to the cam-shaft B of the loom and operates upon the yarn-drawing device through the intervention of the treadle-lever J^2 , link J^3 , elbow-lever J^4 , link J^5 , and slide J^6 , to the last of which the butt of the yarn-drawing device is secured. The treadle-lever J^2 is fitted with two trucks, j^5 , j^6 , which embrace the rim of the 60 draw-cam J' , and absence of backlash is insured by connecting one of the trucks, j^6 , with the treadle-lever through the intervention of a lever-stock, j^7 , and spring j^8 . The slide J^6 is guided in its movements by means of the 65 guide J^9 , and a guide-eye, j^9 , is provided for the stem j' , and by their action the yarn-drawing device is caused to move across the loom substantially in a straight line. When the 70 yarn-drawing device is advanced to the yarn-holder, the jaws of the nippers j are forced onto the nozzle i^2 of the yarn-tube i' , standing at the time in the proper position for having its yarn drawn out, the slide-spring j^3 yielding, if necessary, to prevent excessive 75 jar. The entrance of the nozzle between the jaws of the nippers opens them, so that the protruding end of the yarn is received between them, and when the yarn-drawing device is drawn backward by the action of the 80 draw-cam J' , the nippers, being pulled off the nozzle of the yarn-tube, close upon the end of the yarn and seize it. The continued backward movement of the yarn-drawing device J then draws the yarn through the shed. As 85 the yarn-drawing device is drawn back rapidly by the draw-cam J' , a bumper, J^9 , is provided to stop it, and in order that there may be no rebound a rebound-stop is provided. This rebound-stop O has preferably a lever 90 form. It is pivoted to the frame of the loom, and its outer end is notched to engage with a pin, o , secured to the lever J^4 , through which motion is transmitted to the yarn-drawing device J . A spring, o' , is provided to cause the 95 rebound-stop to engage with the pin o as soon as that pin passes the shoulder of the notch of the rebound-stop. In order that the rebound-stop may release the yarn-drawing device before it is to be moved to seize a yarn 100 the rebound-stop is connected by a rod, o^2 , with a lever, o^3 , which is fitted with a truck, o^4 , and is pivoted to a bracket projecting from the frame of the loom in the proper position to have its truck operated upon by the draw-cam J' a little before the yarn-drawing device is moved. After the yarn is drawn 105 through the shed of warp-threads the latter is partially closed upon the strand of yarn by the movement of the heddles by the first incline, e , of the heddle-cam E^5 , so that the yarn is held by the pressure of the warp-threads, and then the strand of yarn in the shed is cut loose from the yarn-tube, so that the strand 110 may be driven up by the lay and that the yarn-holder may be shifted to place the next 115 yarn required in position to be drawn into the shed. The cutting loose of the yarn is effected by means of a cutting device, which we 120

prefer to be a pair of shears, P, that is located at a sufficient distance in the loom inside of the nozzles of the yarn-tubes—say about one and one-half inch—to leave the cut end of 5 yarn protruding from the nozzle of the yarn-tube. The blades of the pair of shears are supported by being pivoted to a bracket, P', and they are operated, preferably, by means of the cutting-cam P², which is secured to the 10 cam-shaft B, and a spring, P³, acting antagonistically to that cam P². To this end the shanks of the blades are slotted and inclined in opposite directions, and a pin, p, is fitted to slide in the slots. This pin is held by a swing- 15 ing arm, p', which is connected by a pivot, p², with the bracket P', and it is connected by a rod, p³, with the lever P⁴, upon which the cutting-cam P² operates through the intervention of a truck. The cutting-cam P², when raising 20 the rear end of the lever P⁴, depresses its front end and draws the pin p through the diverging slotted shanks of the shear-blades, thereby causing them to close and cut the 25 yarn. Then the onward passage of the cutting-cam past the lever permits the rear arm of that lever P⁴ to be drawn downward by the spring P³. The front end of the lever P⁴ is correspondingly raised, and the shear-blades are opened to permit the yarn-drawing device 30 vice to pass between them and seize the end of the yarn which is next to be drawn across the loom.

Before the strand of yarn in the shed is beaten up the end held by the yarn-drawing device should be released by opening the jaws 35 of the forceps. For this purpose the opener Q (more fully represented at Figs. 11 and 12) is provided. It consists, substantially, of a pivoted wedge, which is forced between the 40 nippers by means of the opening-cam Q', which is secured to the main cam-shaft B. The opening-cam operates upon the opener Q through the intervention of a lever, Q², and rod q, the last of which is connected with the 45 stock q' of the opener Q. The form of the opening-cam Q' is such as to leave the opener between the nippers until the end of the strand of yarn is drawn from them by the beating up of the strand. Then the opening- 50 cam releases the opening-lever Q², and the opener Q is withdrawn from between the nippers by means of a spring, Q³, which is connected with the opening-lever Q².

In order that the operation of the yarn-drawing device may be rendered absolutely 55 certain it is expedient that the end of the yarn which is seized by the nippers should be materially longer than is necessary to form the pile of the strand of chenille at the needle side of the loom, which in this example is the right-hand side thereof. As the excess of 60 yarn would be wasted if the nippers should be drawn back far enough to clear the reed of the lay before they are opened, the nippers 65 j (as previously described) are connected with the needle-stem j' through the intervention of

the movable shank j², and when the yarn-drawing device is drawn back to its full extent by the cam J' the nippers are left close to the warp-threads and in the way of the reed 70 of the lay, and the nippers are opened in this position. Then a supplementary backward movement is imparted to them, so that they are withdrawn out of the way of the reed of the lay. This supplementary backward movement is preferably imparted to the nippers by the opening-cam Q'. For this purpose the opener Q is fitted with a horn, q², Fig. 11, which, when the opener is forced between the nippers to open them, is forced against the end 75 j¹⁰, Fig. 15, of the nipper-shank and pushes it backward, thus moving the nipper-jaws out of the way of the advancing reed of the lay. When the opener Q is withdrawn from the nippers, as previously described, the horn q² 80 being also withdrawn from the front end of the nipper-shank, permits the spring j³ to restore the nippers to their forward or normal position for advancing to seize the yarn. The strand of yarn is beaten up by means of the 85 lay F'; but before the yarn is beaten up the shed is closed by the operation of the second incline, e', of the heddle-cam E⁵ upon the heddles. The lay F' is fitted in the usual manner with a reed, F, through the dents of which 90 the warp-threads are passed. The lay F' is connected by arms f with a rock-shaft, f', and is operated by the lay-cam F², which is secured to the main cam-shaft B of the loom, 95 the cam operating upon the lay rock-shaft f' through the intervention of an arm, f², which is fitted at its end with a truck to run on the lay-cam F². We prefer to effect the return movement of the lay by a spring, F³, which 100 operates antagonistically to the lay-cam F². 105

In order that the edge of the fabric or selvage at the needle side of the loom may be uniform, the ends of the yarns protruding there are trimmed or cut off in line. We effect this trimming by means of a selvage-trimmer, and we prefer to arrange this trimmer closer to the breast-beam G of the loom than the yarn-drawing device is, so that the trimming may be effected after the yarns are beaten up. To this end a selvage-trimmer, 110 R, is located at the side of the loom opposite to that at which the yarn-holder I is placed, and is arranged to cut the yarns as they are brought to the breast-beam G by the taking up of the woven fabric by the cloth-roll. This selvage-trimmer is formed, 115 by preference, of a fixed blade, r, secured to the breast-beam, and a vibratable cutting-blade, r', which is operated in the loom we are describing, by connecting it by a rod, r², with an arm, r³, secured to the lay rock-shaft f', so that the movable blade r' is alternately opened and closed upon the fixed blade r. 120 125

The opening of the sheds of warp-threads for the drawing of the colored yarns through 130 them is effected by moving the leaves of heddles E E' E², through which the warp-threads

cases to hold the separate yarns. This system of holding masses of yarn in cases differs materially from the previous systems of holding the yarns upon spindles or bobbins, and it is attended with the advantage that a large number of masses of yarn of different colors or shades can be held in a separate condition in a comparatively small space, and that each particular mass of yarn (whether in the form of a cop or ball) can, as wanted for use, be moved successively (by shifting the yarn-holder) to the same position for having its yarn drawn from the mass in the case in which it is held.

15 We claim as our invention—

1. The combination, substantially as before set forth, of the shifting yarn-holder constructed with a series of yarn-cases and the corresponding series of yarn-tubes which hold 20 the ends of the yarn and which are connected with said yarn-holder so as to be shifted with it.

2. The combination, substantially as before set forth, of the shifting yarn-holder constructed with yarn-cases, with a tension device to prevent the yarns from rendering too freely from the yarn-cases.

3. The combination, substantially as before set forth, of the shifting yarn-holder with an 30 index of the yarn-cases, which index is arranged upon the yarn-holder and moves with it.

4. The combination, substantially as before set forth, of the shifting yarn-holder with a 35 face index of the yarn-cases.

5. The combination, substantially as before set forth, of the shifting yarn-holder constructed with yarn-cases, with the stop by which the said yarn-holder is held when a yarn 40 is to be drawn from one of the yarn-cases.

6. The combination, substantially as before set forth, of the shifting yarn-holder constructed with yarn-cases, with a yarn-drawing device, by means of which the yarn is 45 drawn from the yarn-cases across the loom.

7. The combination, substantially as before set forth, of the shifting yarn-holder constructed with yarn-cases and the yarn-drawing device, with the yarn-cutter by means of 50 which the drawn strand of yarn is cut loose from the yarn-holder.

8. The combination, substantially as before set forth, with a shifting yarn-holder con-

structed with yarn-cases, of the yarn-drawing device and the selvage-trimmer, whereby the 55 ends of the strands of yarn which have been seized by the yarn-drawing device are trimmed to a substantially uniform length.

9. The combination, substantially as before set forth, of the yarn-tube and the yarn-drawing device constructed with spring-nippers adapted to be opened by being forced against the nozzle of said yarn-tube.

10. The combination, substantially as before set forth, of the spring-nippers of the yarn-drawing device with the rod by which they are moved, and the intervening sliding shank and spring.

11. The combination, substantially as before set forth, of the nipper-jaws of the yarn-drawing device with the opener by which they are opened when their grip upon the yarn is to be relaxed, and the opening-cam by which said opener is operated.

12. The combination, substantially as before set forth, of the nippers of the yarn-drawing device, the opener, and a cam for imparting the supplementary backward movement to the nippers.

13. The combination, substantially as before set forth, of the yarn-drawing device with the rebound-stop.

14. The combination, substantially as before set forth, of the doup-heddles, the tension device for the warp-threads controlled by said 85 heddles, and the tension-relaxing device by which the acting force of said tension device is varied.

15. The combination, substantially as before set forth, of the whip-roll, the tension-weight 90 thereof, the tension-lever, and the tension-cam by which said lever is operated.

16. The combination, substantially as before set forth, of the three leaves of heddles, the heddle-lever, the connecting-rods between two 95 of said leaves and the said heddle-lever, and the connections between one of said two leaves and the third leaf of heddles.

In witness whereof we have hereto set our hands this 29th day of December, A. D. 1886. 100

HALCYON SKINNER.
EUGENE TYMESON.
